MAINE.

ELASTIC HEEL.

973,026.

Specification of Letters Patent. Patented Oct. 18, 1910.

Application filed December 4, 1909. Serial No. 531,336.

To all whom it may concern:

Be it known that we, ROLON E. FOSTER and PHILIP W. PRATT, of Boston, in the county of Suffolk and State of Massachusetts, have invented certain new and useful Improvements in Elastic Heels, of which the following is a specification.

This invention relates to boot and shoe heels, made of elastic material such as rubber, and the invention has particular reference to heels having a form adapted to serve as a support for the arch of the foot.

The object of the invention is to provide a non-slipping and elastic heel tread which has an integral projection from one side of the usual breast line, the said forward projection being provided with a plug of suitable material which will make the said forward projection sufficiently less elastic than the body of the heel so that the said projection, although formed of a generally elastic material, will still provide sufficient support to prevent what is known as a "breaking down" of the arch of the foot.

To these ends the invention consists in the heel substantially as hereinafter described and claimed.

Of the accompanying drawings,—Figure 1 is an under plan. Fig. 2 is a top plan. Fig. 3 represents a section on line 3—3 of Fig. 2. Fig. 4 represents a front elevation of the heel.

Similar reference characters indicate the same or similar parts in all of the views.

The body 10 of the heel is shown as having a thickness to adapt it to serve as an entire heel. But it is to be understood that, if it is applied to a heel having leather lifts of the same general shape as in the present drawings, that is, with a forward projection, the said body 10 may be only what is termed a "half heel"; that is, a body having a thickness of, say, one or two leather lifts.

The forward projection 11, is integral with the body 10, and has molded therein a plug 12 which may be of any preferred shape, and which may be of any suitable material to reduce the resilience of the said

forward projection. In the drawings, said plug 12 is intended to illustrate a structure 50 such as claimed in the application 501,748, filed June 12, 1909, by Philip W. Pratt.

The heel may be provided with one or more additional plugs 13 at the rear of said heel, these last mentioned plugs serving the 55 usual purpose of preventing slipping. Of course the plug 12 in the projection 11 also serves to prevent slipping.

As best shown in Fig. 4, the side of the heel having the projection 11 is thicker than 60 the other side, and consequently the projection itself is thicker than the other side of the body of the heel, so as to provide a better support for the arch of the foot.

We do not limit ourselves to the exact 65 shape of the projection shown, as it may be considerably longer than illustrated in Figs. 1 and 2. But whether long or short, it is provided with a suitably shaped insertion or plug made of a material which is less elastic 70 than the body of said projection. And said plug 12 may extend entirely through the body from bottom to top or only part way as shown in the drawings. Of course, the heels are made rights and lefts. The one illustrated in the drawings is for a left shoe or boot.

Instead of providing an insertion or plug 12 exposed at the wear surface of the heel, it may be below such surface; that is, contained entirely within the body 10. Or it may extend rearward from the face of the projection, in which case it may be in the form of a wedge tapering rearwardly. And instead of being made of fabric and rubber, 85 it may be of a rubber composition which, when the heel is vulcanized, will be harder than the rubber which incloses it. In fact, any structure which decreases the resilience 90 of the projection, and which will preserve and enhance the arch-supporting function of the projection 11, comes within the scope of the invention.

Having now described our invention, what we claim is:

A heel having a body of elastic material,

said body having an integral projection forward from one side of the usual breast line to form an arch support, the said projection having a greater transverse thickness than 5 that of the other side of the body of the heel, said projection having an insertion or plug of material which is less elastic than the body of said projection.

In testimony whereof we have affixed our signatures in presence of two witnesses.

ROLON E. FOSTER.
PHILIP W. PRATT.
